THREE-STAGE PROPANE FRACTIONATION
OF REDUCED CRUDE OILBruce C. Benedict, Bartlesville, Okla., assignor to
Phillips Petroleum Company, a corporation of
Delaware

Application December 23, 1948, Serial No. 66,993

15 Claims. (Cl. 196—14.46)

1

This invention relates to propane-fractionation of lubricating oil stocks. In one of its more specific aspects it relates to a method for the treatment of low asphalt-containing lubricating oil stocks for the separation and recovery of lubricating oil fractions. In a still more specific aspect it relates to a process for the separation and recovery of lubricating oil fractions from crude lubricating oil stocks containing some asphaltic material by fractionation with liquid propane wherein the asphaltic material is not precipitated and caked in the oil fractionating apparatus.

Deasphalting petroleum oils and more particularly reduced crude oils from which distillate lubricating oil fractions have been removed is old in the art. Such operations are usually carried out at temperatures between about 70° and 140° F. to take advantage of the precipitating action of propane on the heavy asphaltic constituents of the oil. It has also been recognized for many years that a fractionating effect can be obtained with propane-oil mixtures at temperatures ranging from about 140° F. up to the critical temperature of propane. Utilizing the unique properties of liquid propane whereby increasing temperatures result in progressive rejection of hydrocarbons in such a manner that the higher molecular weight components and the more aromatic and naphthenic components are separated first and the lighter components and more paraffinic hydrocarbons last, a combination of low temperature distillation and solvent extraction is achieved. However, due to the difficulties involved in working at high pressures and in close proximity to the critical temperature of propane, commercial exploitation was unknown until quite recently.

It has been found, however, that some low-asphalt content reduced crude lubricating oils may be fractionated continuously by liquid propane at a high temperature and under correspondingly high pressure, while other such crude oil stocks can be fractionated for only short periods of time. In this latter case it has been found that the fractionating equipment became plugged with a deposit of asphaltic material. This asphaltic material had apparently been precipitated from the oil upon contact with the high temperature liquid propane.

An object of my invention is to devise a continuous process in which low asphalt-containing reduced crude lubricating oil stocks are fractionated with propane for the separation and recovery of lubricating oil constituents.

2

Another object of my invention is to devise a method for the separation and recovery of lubricating oil constituents from such crude oil stocks by fractionation with liquid propane without the formation of hard asphaltic deposits in the propane fractionation apparatus. Still another object of my invention is to devise a continuous process for the separation and recovery of lubricating oil fractions from low asphalt-containing reduced crude oil stocks suitable for the manufacture of lubricating oils by liquid propane fractionation wherein the asphaltic constituents are maintained in a form which does not adhere as a hard mass to the fractionation equipment. Still other objects and advantages of my invention will be obvious to those skilled in the art upon reading the following disclosure, which, taken with the attached drawing, forms a part of this specification.

In preparing to apply the above mentioned unique properties of liquid propane to actual commercial separation of certain grades of lubricating oil from residual stocks a hitherto unrecognized problem was encountered. Upon treating some Mid-Continent reduced crude oil stocks having low asphalt content with liquid propane in a countercurrent contacting tower at a propane to oil volume ratio of about 7:1 with temperatures ranging from about 195° F. at the top to about 175° F. at the bottom of the tower, an SAE 40 oil was separated as overhead product. On the other hand, when a very similar Mid-Continent reduced crude oil stock low in asphalt content was charged to the process under the same operating conditions a similar fraction of lubricating oil was initially obtained but the column rapidly filled with a hard asphaltic material in the stripping section, thereby making continuous operation impossible. In this second case, a third phase, that is, a semi-fluid asphaltic phase was apparently produced along with a propane-rich light oil fraction and an oil-rich solution of propane in heavy oil. Upon contacting the charge oil with liquid propane this third phase when first formed was sufficiently fluid to flow nearly to the bottom of the column before the ascending propane had washed it sufficiently to cause it to set to a hard cake. Upon continued operation this asphalt cake builds up in the column until complete closure of the column occurs.

In a study of three well known Mid-Continent reduced crude oils which have been long recognized as excellent sources of lubricating oil

stocks hard asphaltic deposits were formed in the fractionating equipment when fractionating two of these stocks with liquid propane while the third was fractionated with propane continuously and without difficulty. It has also been found that some West Texas reduced crude oils can be fractionated with propane while others cannot on account of asphalt deposition. It is therefore realized that propane fractionation cannot be universally applied to all so-called low asphalt crude lubricating oil stocks. The reason why apparently similar low-asphalt oils behave so differently is not known.

I have now discovered a method for the operation of a fractionating column wherein such low-asphalt lubricating oil stocks may be continuously fractionated with propane for separation of lubricating oil fractions.

The figure shows diagrammatically, partly in elevation and partly in section, one form of apparatus in which to practice the process of my invention.

The apparatus consists essentially of three fractionating towers identified by reference numerals 12, 16 and 18. These towers are equipped with top tower heating coils 23, 24 and 25 having pipe connections 26, 28 and 30, respectively, for inlet and outlet of heating fluids. Each column may be equipped with packing or contacting apparatus 27 which may be merely horizontally disposed slats or it may be trays of conventional type or any other type of packing or liquid-liquid contacting apparatus. The main point is that this packing material should be such as to promote efficient contacting between the several liquid phases in the process. Of course, the process may be operated without any contacting apparatus 27 but in such cases larger towers are required and liquid-liquid contactings are not especially efficient. Thus, I prefer to use some suitable type of internal contacting apparatus.

The top of tower 12 is connected with about a mid-point of tower 16 by a pipe 13. Tower 16 has an overhead pipe 17 for product removal while pipe 19 conducts material from tower 18 to about a mid-point of tower 16. Pipes 13 and 19 are equipped with heaters 32 and 34, respectively. From the bottom of tower 12 a pipe 14 conducts bottoms to about a mid-point of tower 18 while this latter tower has a bottom outlet pipe 20 which serves to remove one final product of the process. The centrally disposed tower 16 has a bottom outlet connected by a pipe 15 leading to about a mid-point of treating tower 12. Pipes 10 and 10A are for introduction of feed stock into the tower 12. The towers 12, 16 and 18 are each equipped with propane inlet pipes 11, 22 and 21, respectively, at points near the bottom of these towers. Pipe 14 is equipped with a heater 35 while pipe 15 is equipped with a cooler 33. These several heaters and coolers may be used for heating or for cooling as hereinbefore mentioned or they may be used for cooling or heating as operating conditions of the process require.

Pilot plant propane fractionation of a Mid-Continent reduced crude oil stock of known asphalt depositing tendencies has demonstrated that a propane asphalt precipitating operation in which a very small amount of asphalt is precipitated is not sufficient to solve the problem. When such stocks are treated for removal of the light oil content, the treating column is quickly plugged by precipitated asphalt. This plugging is particularly severe when attempting to prepare

an SAE 50 oil from certain low-asphalt crude lubricating oil stocks from which SAE 10 and 20 viscosity oil fractions have already been removed and the indication is that three liquid phases are produced at the point of entrance of the feed stock into the propane column. On the other hand, if lower temperature conditions and somewhat lower propane to oil ratios are maintained the phase relationships are such that a third hard asphalt phase is not deposited but only high viscosity oil is separated. Under such conditions it is impossible to prepare a narrow viscosity range lube oil stock as an overhead product which, of course, is the primary object of propane fractionation. Due to the low propane-oil ratio the bottoms product is not stripped of all the oil content desired to be included in the overhead product. To correct this deficiency, I prefer to operate the main extraction column under such conditions as to produce a relatively broad overhead fraction which may contain components from SAE 30 to 70, inclusive. This wide viscosity range fraction is then subject to a second fractionation under relatively severe temperature conditions, that is, a top tower temperature of about 200° with a bottom tower temperature of about 180°. This high top tower temperature, coupled with a suitable propane to oil ratio, assists in fractionating out an SAE 40 or 50 oil as the overhead product.

The incompletely stripped bottom product from the main fractionator may also be stripped of desirable oils in a third fractionating column in which danger of the formation of the hard asphalt deposit is avoided due to the removal of the relatively light oils in the first column. The overhead oils stripped in the asphalt stripping column are introduced into the second column which was hereinbefore described as operating under severe conditions on the overhead product from the first tower. The overhead fraction from column 18 (the third tower) is also passed into the second column (16) at a mid-point and the bottoms from the fractionation of both overhead fractions consist of relatively heavy oils and this product is returned to the first tower at about the feed plate at which point it assists in preventing the precipitation of the asphalt phase since the asphaltic material is relatively soluble in this heavy recycled oil.

Specific example

A reduced crude oil stock of about 850° F. initial boiling point is prepared by distillation to remove SAE 10 and 20 viscosity fraction. This prepared crude charge then contains all the remaining components of higher viscosity than the SAE 20 oil and is then fractionated by means of propane to produce about an SAE 50 oil as overhead product and a final heavy oil-asphalt product according to the following sequence of steps and under the following conditions.

This prepared reduced crude oil stock is charged to the first propane column 12 through the line 10A. This column has been previously filled with liquid propane at a pressure of about 450 pounds per square inch gauge. All pressure given herein are gauge pressures and are given in pounds per square inch. The charge oil is introduced into this column at a temperature of about 150° F. Liquid propane at about 140° F. is then pumped into the column through line 11 at a rate such that the volume ratio of the propane to the charge oil is about 4:1. At the point of introduction of the oil charge into the column,

some oily constituents dissolve in the propane while other oily constituents remain as an oil phase and a third phase may separate. When a third phase separates it is a liquid phase high in asphalt content. The oil phase and this high asphalt content phase tend to descend through the up-flowing liquid propane. During this countercurrent movement of liquids the propane stream serves to strip the downflowing oils of a portion of their oil content which was not previously dissolved by the propane at the feed plate level. In the upper or fractionating section of vessel 12, that is, the portion above the feed inlet, heavier and more aromatic and naphthenic portions of dissolved oil are precipitated from the oil-propane solution by maintaining a high temperature in the top of the column. In propane fractionation work, it is known that the higher the temperature of the propane the less soluble are the lighter oils in propane, thus, a certain viscosity oil will be precipitated at a given temperature and by raising the temperature an oil fraction of lower viscosity is precipitated. Thus, the top section of vessel 12 operates essentially as a refluxing section by knocking back or precipitating the highest viscosity components from the top of the tower so that components of a lower viscosity may be removed as top product. The propane to oil ratio, however, in this column 12 is such that at a top tower temperature of 160° F. a relatively wide viscosity range oil is produced. The low propane to oil ratio is necessitated by the tendency of the asphalt content of some crude oil stocks to precipitate in the primary treating tower.

This relatively wide viscosity range overhead fraction from the primary tower 12 due to the low top tower temperature contains a relatively large amount of high viscosity oils which are then removed in a second fractionation tower 16. In column 16 this oil stock is fractionated by a temperature gradient above the feed point. On passing through line 13 from the top of tower 12 to the mid-point of tower 16 this overhead product is heated from about 160° F. to about 190° F. so that this stock may be introduced into tower 16 at about this temperature. This tower is, of course, previously filled with liquid propane and propane is now pumped into this tower through a line 22 at about one volume per volume of charge oil to vessel 12. The propane inlet temperature to vessel 16 is about 180° F. The temperature at the top of vessel 16 is maintained by the heating coil 24 at a temperature of about 195° to 200° F. This relatively high top tower temperature precipitates the highest viscosity oil components from the oil-propane solution rising from the feed point toward the top of the tower. This precipitated high viscosity oil settles downward in this tower and finally accumulates as an oil phase in the bottom of the tower. During the settling of the precipitated oil the upward flowing propane tends to strip the more soluble portions of the oil and return them to the top of the tower.

The partially stripped oil and asphalt-containing bottoms which accumulate in vessel 12 are withdrawn through line 14 and introduced into about a mid-point of vessel 18. This bottoms product leaves vessel 12 at about 140° F. and is heated in transit by heater 35 to a temperature of about 170° prior to introduction into the treating vessel 18. Liquid propane which, of course, fills this vessel is introduced into the bottom through line 21 and is maintained at a

temperature of about 160° F. The heating coil 25 in the top of this vessel keeps the top tower temperature at about 180° F. for refluxing purposes similar to that described in relation to the operation of vessels 12 and 16. This vessel is operated under a pressure of 550 pounds. The solution of heavy oil in propane which leaves the top of vessel 18 through line 19 is heated in heater 34 prior to its introduction into about a mid-point of vessel 16. While this propane solution from the top of vessel 18 is described as being added to vessel 16 at about the mid-point, it is intended to be added thereto at about the point of introduction of the propane solution from the top of vessel 12. These two streams need not be introduced into vessel 16 at exactly the same point since the dissolved oil in the two streams is different grade oil but they should be added at points separated by preferably only a short space. The oil from pipe 19 is a relatively high viscosity oil while that in pipe 13 will have a considerably lower average viscosity. However, for general operation considerations, I prefer to add these two streams to vessel 16 at about the same point. A heavy oil which accumulates in the base of vessel 18 is withdrawn through the bottoms drawoff pipe 20 and this material may be passed to a propane recovery unit or to subsequent propane fractionation steps, not shown, for recovery of still higher viscosity oils if desired.

A small volume of oil-rich phase is preferably maintained in the bottom of each of the three fractionating columns. The level of each of these several oil-rich phases is maintained somewhat above the points of additions of the propane so that as the newly added propane reaches the liquid-liquid interfaces it will be saturated or nearly saturated with soluble oil at the temperature conditions at that point in each of these several columns. The amount of propane introduced into column 18 through line 21 at a temperature of about 160° F. amounts to about three volumes of propane per volume of oil charge to the primary fractionator 12.

In summing up the described operation, generally, vessel 12 is operated with a bottom temperature of 120°-145° F., a middle point temperature of 145°-155° F., and a top temperature of 155°-165° F. at about 400-600 pounds pressure. The column 16 is operated at a bottom, a middle, and a top temperature of 175-185° F., 185-190° F., and 190-210° F., respectively, at a pressure of roughly 600-700 pounds. The column 18 is operated at a bottom, middle, and top temperature of 155°-165° F., 165°-175° F., and 175-185° F., respectively, at a pressure of roughly 500-700 pounds. Into column 12 is introduced per volume of charge oil 3 to 6 volumes of propane, in column 16 is introduced 1 to 3 volumes of propane, and in column 18 2 to 5 volumes of propane. The overall propane to oil ratio is 6:1 to 14:1.

In the drawing is shown the line 15 connecting the bottom of vessel 16 with an oil feed line 10 so that the oil phase from vessel 16 may become mixed with charge oil so that the heavier and less paraffinic hydrocarbons separated from vessel 16 may have ample opportunity to become thoroughly mixed with the charge oil before its introduction into the primary treater 12. In this manner, these recycle oils have ample opportunity to exert a solubilizing effect on the asphaltic constituents of a charge oil so that these asphaltic materials will not be precipitated as hard cake asphalt in the primary treater

12. A cooler 33 may be inserted in line 15 to cool these recycle oils to the desired temperature of the mid-point of vessel 12 or if desired, the charge oil may be at a temperature sufficiently below 150° F. that the warmer oil in line 15 will make the mixture entering vessel 12 at a desired feed inlet temperature.

The propane-oil solution leaving the vessel 16 through the top drawoff line 17 may be passed to a propane recovery unit or may be passed to a unit for further fractionation, if desired, or it may be passed to a refining step, if desired. Whatever the disposal of the propane and oil solution from pipe 17 and the oil-propane solution from pipe 20, propane will be recovered ultimately and returned to a propane run storage tank, not shown, for recycling in this system.

Contacting apparatus should preferably be used in the towers 12, 16 and 18 so that these towers may be as small as possible and yet promote efficient contacting between propane and oil. Any type of contacting stages desired may be used provided of course they are suitable for the problem at hand. To maintain proper temperature gradients throughout the lengths of the several treaters 12, 16 and 18 it may be desirable to insert multiple heat exchange steps. The particular number of these steps, their location and temperatures maintained thereby are such as to maintain the desired temperatures and temperature gradients.

Such auxiliary equipment as valves, pumps, pressure and temperature regulators, flow meters, level controllers, are not shown for purposes of simplicity. The installation and operation of such equipment is well known in the art. It will be obvious to those skilled in the art that many variations in operation conditions may be made, such as slight changes in temperatures and pressures, or even ratio of propane to oil, for accomplishing the desired and specific fractionation problem and yet remain within the intended spirit and scope of my invention.

Having disclosed my invention, I claim:

1. A process for fractionating an asphalt-containing crude lubricating oil stock comprising maintaining a body of said oil in a first treating zone, maintaining a body of liquid propane containing dissolved oil above said body of oil in said first zone, said bodies meeting at a common interface, introducing a stream of liquid propane into said body of oil, introducing a stream of said asphalt-containing lubricating oil stock into said body of liquid propane containing dissolved oil at a midpoint of said zone, removing propane containing dissolved oil from the top and asphalt-containing oil from the bottom of said first treating zone; maintaining a body of propane containing dissolved oil in a second treating zone at a temperature higher than the temperature of the body of propane containing dissolved oil in said first zone, maintaining a body of an oil rich phase below said body of propane containing dissolved oil in said second treating zone, said latter two bodies meeting at a common interface, introducing liquid propane into this latter oil rich phase, passing said removed propane containing dissolved oil from said first treating zone into the midpoint of said body of propane containing dissolved oil in said second treating zone, removing propane containing dissolved oil from the top of said second zone and recovering the oil as one product of the process, removing a stream of oil rich phase from the second treating zone and introducing it into said first treating zone at the

5 point of introduction of said asphalt-containing lubricating oil stock; maintaining a body of propane containing dissolved oil in a third treating zone, maintaining a body of an oil rich phase below said body of propane containing dissolved oil in said third treating zone a said latter two bodies meeting at a common interface, introducing liquid propane into this latter oil rich phase, passing said removed asphalt-containing oil from 10 said first zone into the midpoint of said body of propane containing dissolved oil in said third treating zone, removing propane containing dissolved oil from top of said third zone and passing this removed propane containing dissolved oil 15 into the body of propane containing dissolved oil in said second treating zone, removing oil rich phase from the bottom of said third treating zone and recovering oil containing asphalt as a second product of the process.

20. 2. The process of claim 1 wherein a higher temperature is maintained at the top of each of the three treating zones than at the bottom of these zones and each zone is maintained under sufficient pressure that all contents thereof are 25 maintained in the liquid state.

3. The process of claim 1 wherein the temperature of the oil rich phase in the first treating zone is maintained between the limits of 120° to 145° F., the temperature at the raw oil feed inlet point is maintained between the limits of 145° to 155° F., and the temperature at the point of outlet of the propane containing dissolved oil is maintained between the limits of 155° to 165° F., the temperature of the oil rich phase in the second treating zone is maintained between the limits of 175° to 185° F., the temperature at the point of introduction of the streams of propane containing dissolved oil from the first and third zones is maintained between the limits of 185° to 190° F., and the temperature at the point of outlet of the propane containing dissolved oil is maintained between the limits of 190° to 210° F., and the temperature of the oil rich phase in the third treating zone is maintained between the limits of 155° to 165° F., the temperature at the point of introduction of the stream of oil-rich phase from the first zone is maintained between the limits of 165° to 175° F., and the temperature at the point of outlet of the propane containing dissolved oil in the third zone is maintained between the limits of 175° to 185° F.; the pressures maintained in the three treating zones are, respectively, 450 pounds per square inch, 640 pounds per square inch and 550 pounds per square inch.

55. 4. The process of claim 3 wherein four volumes of propane per volume of oil charge stock is introduced into the first treating zone, one volume propane per volume oil charge stock is introduced into the second treating zone and three volumes propane per volume of oil charge stock are introduced into the third treating zone.

60. 5. In the propane fractionation of lubricating oil constituents from low asphalt-content reduced crude lubricating oil stocks with liquid propane 65 wherein solid asphaltic material precipitates upon initial contact with the propane and adheres to and plugs the fractionating apparatus in the region adjacent and below the raw feed entry point, a process for continuously carrying out this fractionation operation without precipitating said asphalt and plugging said apparatus comprising maintaining a body of said oil in a first treating zone, maintaining a body of liquid propane containing dissolved oil above said body of oil in said first zone, said bodies meeting at a 70 75

common interface, introducing a stream of liquid propane into said body of oil, introducing a stream of said low asphalt-content reduced crude lubricating oil stock into said body of liquid propane containing dissolved oil at a midpoint of said body of propane containing dissolved oil, removing propane containing dissolved oil from the top and asphalt-containing oil from the bottom of said first treating zone; maintaining a body of propane containing dissolved oil in a second treating zone at a temperature higher than the temperature of the body of propane containing dissolved oil in said first zone, maintaining a body of an oil rich phase below said body of propane containing dissolved oil in said second treating zone, said latter two bodies meeting at a common interface, introducing liquid propane into this latter oil rich phase, passing said removed propane containing dissolved oil from said first treating zone into the midpoint of said body of propane containing dissolved oil in said second treating zone, removing propane containing dissolved oil from the top of said second zone and recovering the oil as one product of the process, removing a stream of oil rich phase from the second treating zone and introducing it into said first treating zone at the point of introduction of said asphalt-containing lubricating oil stock; maintaining a body of propane containing dissolved oil in a third treating zone, maintaining a body of an oil rich phase below said body of propane containing dissolved oil in said third treating zone, said latter two bodies meeting at a common interface, introducing liquid propane into this latter oil rich phase, passing said removed asphalt-containing oil from said first zone into the midpoint of said body of propane containing dissolved oil in said third treating zone, removing propane containing dissolved oil from top of said third zone and passing this removed propane containing dissolved oil into the body of propane containing dissolved oil in said second treating zone, removing oil rich phase from the bottom of said third treating zone and recovering oil containing asphalt as a second product of the process.

6. The process of claim 5 wherein a higher temperature is maintained at the top of each of the three treating zones than at the bottom of these zones and each zone is maintained under sufficient pressure that all contents thereof are maintained in the liquid state.

7. The process of claim 5 wherein the temperature of the oil rich phase in the first treating zone is maintained between the limits of 120° to 145° F., the temperature at the raw oil feed inlet point is maintained between the limits of 145° to 155° F., and the temperature at the point of outlet of the propane containing dissolved oil is maintained between the limits of 155° to 165° F., the temperature of the oil rich phase in the second treating zone is maintained between the limits of 175° to 185° F., the temperature at the point of introduction of the streams of propane containing dissolved oil from the first and third zones is maintained between the limits of 185° to 190° F., and the temperature at the point of outlet of the propane containing dissolved oil is maintained between the limits of 190° to 210° F., and the temperature of the oil rich phase in the third treating zone is maintained between the limits of 155° to 165° F., the temperature at the point of introduction of the stream of oil-rich phase from the first zone is maintained between the limits of 165° to 175° F., and the temperature at the

5 point of outlet of the propane containing dissolved oil in the third zone is maintained between the limits of 175° to 185° F.; the pressures maintained in the three treating zones are, respectively, 450 pounds per square inch, 640 pounds per square inch and 550 pounds per square inch.

8. The process of claim 5 wherein four volumes 10 of propane per volume of oil charge stock is introduced into the first treating zone, one volume propane per volume oil charge stock is introduced into the second treating zone and three volumes propane per volume of oil charge stock are introduced into the third treating zone.

9. In the propane fractionation of lubricating 15 oil constituents from low asphalt-content reduced crude lubricating oil stocks with liquid propane wherein solid asphaltic material precipitates upon initial contact with the propane under propane fractionation conditions and adheres to and plugs the fractionating apparatus in the region adjacent and below the raw feed entry point, a process for continuously carrying out this fractionation operation without precipitating said asphalt and plugging said apparatus comprising 20 maintaining a body of oil in a first treating zone, maintaining a body of liquid propane containing dissolved oil above said body of oil in said first zone, said bodies meeting at a common interface, introducing a stream of liquid propane into said body of oil, introducing a stream of said reduced 25 crude lubricating oil stock containing some of said asphalt into said body of liquid propane containing dissolved oil at an intermediate point of said zone, removing propane containing dissolved oil from the top and oil containing asphalt in solution from the bottom of said first treating zone and recovering oil containing asphalt in solution from said removed bottoms as one product of the process; maintaining a body of propane 30 containing dissolved oil in a second treating zone at a temperature higher than the temperature of the body of propane containing dissolved oil in said first zone, maintaining a body of an oil rich phase below said body of propane containing dissolved oil in said second zone, said two 35 bodies meeting at a common interface, introducing liquid propane into this latter oil rich phase, passing said removed propane containing dissolved oil from said first treating zone into an intermediate point of said body of propane containing dissolved oil in said second treating zone, removing propane containing dissolved oil from the top of said second zone and recovering the oil as a second product of the process, removing 40 a stream of an oil phase comprising aromatic and naphthenic constituents from the bottom of said second zone and passing at least a portion of this stream into the first zone at the reduced crude oil feed inlet level thereof.

10. The process of claim 9 wherein the pressures in both treating zones are sufficiently high as to maintain the propane in the liquid phase.

11. The process of claim 9 wherein the temperature from said intermediate point to the bottom of the first zone is maintained constant, and the temperature from the midpoint to the top of said first zone is maintained progressively higher than at the bottom of said first zone; and an increasing temperature gradient is maintained from the bottom to the top of the second zone; and both zones are maintained at sufficiently high pressures that the propane therein exists in the liquid phase.

12. The process of claim 9 wherein the temperature from the bottom of the second zone to

the top thereof progressively increases from 180° F. to 200° F., and both zones are maintained at sufficiently high pressures that the propane therein exists in the liquid phase.

13. The process of claim 9 wherein six volumes of liquid propane per volume of said low asphalt-containing crude lubricating oil feed stock are introduced into the oil rich phase of the first treating zone and two volumes of liquid propane per volume of said low asphalt-containing crude lubricating oil feed stock are introduced into the second treating zone; and wherein the temperature from the bottom of the second zone to the top thereof progressively increases from 180° F. to 200° F., and both zones are maintained at sufficiently high pressures that the propane therein exists in the liquid phase.

14. The process of claim 9 wherein from 3 to 6 volumes of liquid propane per volume of said low asphalt-containing crude lubricating oil feed stock are introduced into the oil-rich phase of the first treating zone and from 1 to 3 volumes of liquid propane per volume of said low asphalt-containing crude lubricating oil feed stock are introduced into the second treating zone; and wherein the temperature from the bottom of the second zone to the top thereof progressively increases from 180° F. to a temperature within the limits of 195° to 210° F.

15. In the propane fractionation of lubricating oil constituents from low asphalt-content reduced crude lubricating oil stocks with liquid propane wherein solid asphaltic material precipitates upon initial contact with the propane under propane fractionation conditions and adheres to and plugs the fractionating apparatus in the region adjacent and below the raw feed entry point, a process for continuously carrying out this fractionation operation without precipitating said asphalt and plugging said apparatus with deposited asphalt comprising maintaining a body of oil in a first fractionation zone, maintaining a body of liquid propane containing dissolved oil above said body of oil in said first zone, said

bodies meeting at a common interface, introducing a stream of liquid propane into said body of oil, introducing a stream of said reduced crude lubricating oil stock containing said asphalt into said body of liquid propane containing dissolved oil at an intermediate point thereof, removing propane containing dissolved oil from the top and oil containing asphalt in solution from the bottom of said first fractionation zone and recovering oil containing asphalt in solution from said removed bottoms as one product of the process; maintaining a body of liquid propane containing dissolved oil in a second fractionation zone, maintaining a body of an oil rich phase below said body of propane containing dissolved oil in said second zone, said two bodies meeting at a common interface, introducing liquid propane into this latter oil rich phase, passing said removed propane containing dissolved oil from said first fractionation zone into an intermediate point of said body of propane containing dissolved oil in said second fractionation zone, removing propane containing dissolved oil from the top of said second zone and recovering the oil as a second product of the process, removing a stream of an oil phase comprising aromatic and naphthenic constituents from the bottom of said second zone and passing at least a portion of this stream into the first zone at the reduced crude oil inlet level thereof.
